UNITED STATES PATENT OFFICE.

DANIEL F. MURPHY, OF GRACEVILLE, MINNESOTA.

RETURN-FLUE BOILER.

SPECIFICATION forming part of Letters Patent No. 739,900, dated September 29, 1903.

Application filed August 4, 1902. Serial No. 118,222. (No model.)

To all whom it may concern:

Be it known that I, DANIEL F. MURPHY, a citizen of the United States, residing at Graceville, in the county of Bigstone and State of Minnesota, have invented certain new and useful Improvements in Return-Flue Boilers; and I do hereby declare the following to be a full, clear, and exact description of the invention, such as will enable others skilled in the art to which it appertains to make and use the same.

My invention has for its object to improve the construction and operation of return-flue boilers; and to this end it consists of the novel devices and combinations of devices herein-after described, and defined in the claim.

The invention in its preferred form is illustrated in the accompanying drawings. Therein like characters indicate like parts throughout the several views.

Figure 1 is a vertical longitudinal section taken centrally through a boiler constructed in accordance with my invention; and Fig. 2 is an end elevation, with some parts broken away and others sectioned, of the boiler illustrated in Fig. 1.

Of the parts of the boiler which correspond to the ordinary or old constructions the numeral 1 indicates the main shell or body of the boiler; 2, the dome; 3, the main flue; 4, the return-flues; 5, the outer flue-sheet, and 6 the steam-pipe.

The parts now to be described relate to my improvements.

The numeral 7 indicates the head, and the numeral 8 the approximately cylindrical portion, of a removable supplemental boiler-section, rigidly secured to and within which is a smoke-box 9. This smoke-box 9 is shown as flattened on top, as indicated at 10, and it is provided with a projecting annular end section 11, which is adapted to telescope over the outer end of the main boiler 1 and to be rigidly but detachably secured thereto, as shown, by means of a plurality of machine-screws 12, that engage directly in an annular band 13, directly and rigidly secured upon the outer surface of the said boiler 1. It will be noted that a vertically-extended section 14 connects the flattened portion 10 of the smoke-box 9 with the upper portion of the annular extension 11, and it will be further noted that

the inner edge of the supplemental section 8 is contracted at 15, so as to join the said extension or flange 11, to which it is secured 55 with a steam-tight joint by rivets 16. Long bolts 17 connect the flattened portion 10 of the smoke-box with the top of the supplemental section 8, while short bolts 18 connect the heads of the said smoke-box and supplemental boiler-section. A small armhole or passage 19 opens through the heads of the said sections or parts 9 and 7, this hole being normally closed by a door or cover 20. A steam-conveying pipe 21 opens from the main 65 boiler 1 into the supplemental boiler-section 78, and likewise the water-conveying pipe 22 opens from the said boiler 1 into the said supplemental boiler-section. In order to carry out my scheme of making the supplemental boiler-section readily detachable, the said pipes 21 and 22 are formed in sections, the sections of the same being connected, respectively, by union-joints 23 and 24. In the drawings the pipe 21 is shown at the extreme top of the 75 boiler and the pipe 22 at the extreme lower portion of the same. This has been done for the purpose of clearness of illustration, while, as a matter of fact, it is probable that in actual construction the said pipes would be located to one side or the other of a vertical line drawn through the center of the boiler, this being necessary in many instances to give clearance for other parts of the engine. It would of course in all cases be necessary 85 that the steam-pipe 21 have both ends located above and the water-pipe 22 have both ends located below the level or possible levels of the column of water z , for otherwise proper equalizing action of the steam-pressures and 90 water-levels in the main and supplemental boiler-sections would be interfered with.

It is important to note that the peripheral portion of the water-jacketed smoke-box projects radially outward beyond the cylindrical 95 or peripheral portion of the adjoining end of the boiler and that the interior of the smoke-box follows approximately the cross-section of the end of the boiler at its sides and lower portion and up to a point above the uppermost flues. At a point above the uppermost flues the upper wall of the smoke-box is flattened, so that it stands below the water-level. In virtue of this construction no flues are cut

out by the application of the water-jacketed smoke-box; but, on the contrary, all that surface of the flue-sheet to which it is possible to apply flues or to which flues are ordinarily applied is left exposed to the interior of the said water-jacketed smoke-box.

With my improvement the smoke-box is water-jacketed, so that any and all heat which is radiated through and from the same is caused to heat the surrounding water, transforming the same into steam, and thereby preventing waste of heat. In this manner the supplemental boiler-section effects an economy in the use of fuel and increases the capacity of the boiler.

When it is desired to retube the return-flues⁴, the so-called "supplemental" boiler-section may be readily removed simply by first removing the screw-bolts 12 and disconnecting the sections of the pipes 21 and 22 by means of the unions 23 and 24.

It will of course be understood that I do not

limit myself to the specified construction illustrated; but, on the contrary, my invention is capable of many modifications. The flues ²⁵ can readily be cleaned from either end of the boiler.

What I claim, and desire to secure by Letters Patent of the United States, is as follows:

In a return-flue boiler, a water-jacketed smoke-box, the peripheral surface of which projects radially outward beyond the adjoining cylindrical walls of the boiler, and the inner walls of which fire-box follow approximately the cross-section of the boiler, up to a ³⁰ ³⁵ point above the flues, at which point it is flattened, substantially as described.

In testimony whereof I affix my signature in presence of two witnesses.

DANIEL F. MURPHY.
